UNITED STATES PATENT OFFICE.

JOHN EMMONS BEMIS, OF CEDAR RAPIDS, IOWA.

LEDGER-TRAY.

1,381,902.

Specification of Letters Patent. Patented June 21, 1921.

Application filed June 21, 1920. Serial No. 390,543.

To all whom it may concern:

Be it known that I, JOHN E. BEMIS, a citizen of the United States, and a resident of Cedar Rapids, in the county of Linn and State of Iowa, have invented a new and useful Improvement in Ledger-Trays, of which the following is a full, clear, and exact description.

My invention relates to improvements in ledger trays, and it consists in the combinations, constructions, and arrangements herein described and claimed.

An object of my invention is to provide a device for holding data cards or the like which is extensible longitudinally and laterally, whereby varying numbers of cards may be accommodated and selected cards may be partly withdrawn laterally for reference without removing the same from order in which placed.

A further object of my invention is to provide a device of the type described that is light in weight, compact in size, and which may therefore be placed upon a desk or the like or readily carried from place to place.

A further object of my invention is to provide a device of the type described that is strong and durable in construction and which lends itself readily to ornamental embellishment.

A further object of my invention is to provide a device of the type described that is thoroughly practical commercially.

Other objects and advantages will appear in the following specification, and the novel features of the invention will be particularly pointed out in the appended claims.

My invention is illustrated in the accompanying drawings, forming part of this application, in which—

Figure 1 is a plan view of the device, the dotted lines indicating the position occupied by a portion thereof when in its laterally extended position.

Fig. 2 is a side view of the device, the dotted lines indicating the position assumed by a portion thereof when extended longitudinally,

Fig. 3 is a section along the line 3—3 of Fig. 1,

Fig. 4 is a section along the line 4—4 of Fig. 1,

Fig. 5 is a section along the line 5—5 of Fig. 3.

In carrying out my invention, I provide

similar upright end portions 1 and 2 whose remote sides are parallel and whose adjacent sides are inclined oppositely from the base upward. The ends 1 and 2 are partly incased by casings 3 and 4 respectively, as shown. The casing 3 has a horizontal extension 5 which is formed with vertically disposed side portions 7. The casing 4 has a horizontal extension 6 which is formed with vertically disposed side portions 8. The extensions 5 and 6 are positioned beneath the bottom of the device which consists of a plurality of slats 9, the side portions 7 and 8 serving to prevent lateral spreading of such slats. The casings 3 and 4 may be secured to the end portions 1 and 2 in any suitable manner as by means of screws 10. The latter have another function also, as will be hereinafter set forth. The slats 9, which comprise the bottom of the device each have one end secured to one of the end members 1 or 2, alternate slats being secured to the same end member. The manner in which the slats are secured is pictured in Fig. 5 of the accompanying drawings. Referring thereto, it will be noted that certain slats are secured to the bottom of the end member 1 by means of screws 14, the ends of such slats extending to the end edge of the end member 1. The slats, not secured to the end member 1, do not extend to the end edge of the end member 1 and are arranged to enter mortises 13 which are provided in the end member 1. The connection of certain slats entering into the construction of the bottom is effected with the end member 2 in a precisely identical manner.

Handles 11, adapted to be grasped by the hand, are secured to each of the ends 1 and 2 and may be positioned, as shown.

The extensible movement longitudinally of the ends 1 and 2 with respect to each other, is limited by a guide member 21 which has one end secured to the end member 1. This guide member 21 is provided with a guide slot 22 adapted to receive a guide pin or stud 23 which is secured in one of the slats 9. This last named slat is rigidly secured to the end 2. I also provide a tubular guide member 15, which has an end portion 16 bent upwardly and secured to the inner face of the end 2 in any suitable manner, as by means of a screw 17. The tubular member 15 is slidable in a slightly larger tubular member 18 which has its end bent

upwardly at 19 and secured to the inner face of the end member 1 by means of a screw 20. The tubular members 15 and 18 provide auxiliary means for guiding the ends 1 and 2 during their extensible movement and also serve as a guiding rod for cards (not shown), which are placed between the ends 1 and 2. Such cards are ordinarily provided with slotted openings 10 in their lower edges adapted to engage such tubular members in such a manner as to permit the cards being moved therealong.

To prevent accidental displacement of the cards, I provide side arms. The side arm 15 at one side of the device comprises a member 24, which is bent laterally at 25, the lateral portion being extended between the casing 4 and the end 2, where it is secured in position by means of a screw 10. An opening 28 is provided in the side portion of the casing 4 to permit the lateral portion of the member 24 being placed as described. The member 24 is slidable in a second member 26, which has its end bent 25 laterally and extended through the opening 28 in the side portion of the casing 3 between the end portion of the casing 3 and the end member 1, being secured in position by the screw 10. The side arm the opposite 30 side of the device comprises a member 29 which has one end slidable in a co-operating member 33. The remote end of the member 29 is secured to a laterally extending guide member 31 by means of screws 30. The remote end of the member 33 is likewise secured to a laterally extending guide member 35, which is precisely identical with the guide member 31, by means of screws 34. The guide members 31 and 35 extend through 35 apertures 36 in the side portion of the casings 4 and 3 respectively, being received in guideways 32 and 38 which are provided in such end portions. Consequently, the side arm consisting of the members 33 and 29 is extensible laterally with respect to the device. This extensible movement is limited 40 by the screws 10 which have portions of their length inserted through guide slots 37 which are provided in the guide members 45 31 and 35 (see Figs. 1 and 4).

From the foregoing description of the various parts of the device, the operation thereof may be readily understood. The device is suitable for use in filing systems 50 in which it is desired to keep data cards upon the desk or the like for ready reference. The device is particularly suitable as a tray for ledger cards. It will be understood that the device may be manufactured in different sizes, the size depending upon the size and number of cards ordinarily used. In service the cards are placed in a desired order between the ends 1 and 2, being maintained 55 in position by the side arms and by the arrangement of the tubular guide members

15 and 18 in the aligned slotted openings ordinarily provided in such cards.

When it is desired to segregate certain cards from the others for any purpose without removing the same from the order in which placed, the laterally extensible side arm is moved into its extended position and such cards are likewise moved laterally. For example, suppose the device is being used as a ledger tray. Entries are being 75 posted to certain cards held in the tray. As each entry is posted, the particular card concerned is moved laterally without being entirely withdrawn from its position with respect to the other cards. When the posting has been completed, a recapitulation thereof may be quickly and readily made to determine the accuracy of such posting and to disclose any errors, since all the cards affected by the entries are immediately available without the necessity of examining all the cards in the tray to select those concerned.

The device is light in weight and may therefore be moved by hand from place to 90 place and may be placed within a safe or the like for security and protection of the records.

I claim:

1. A device of the class described comprising a pair of upright end members arranged to face each other, a plurality of horizontally aligned bottom slats, alternate slats being rigidly secured to the same end member, whereby the ends are movable 100 longitudinally with respect to the device, means for limiting the longitudinal movement of said end members, and an extensible side arm connected with the side edges of said end members.

2. A device of the class described comprising a pair of upright end members formed with their adjacent faces inclined oppositely from the base upward, a plurality of horizontally aligned bottom slats arranged 110 between the end members, alternate slats being rigidly secured to the same end member and arranged to enter recesses in the bottom wall of the opposite end member when the device is in its retracted position, means for 115 limiting the extensible movement of the end members, an extensible side arm having one end rigidly secured to a side edge of one of the end members and its opposite end secured to the corresponding side edge of the 120 other end member, and a second side arm having one end secured to a transversely extending guide member slidable in a guideway in one of the end members and having its opposite end secured to a similar transversely extending guide member slidable in 125 a guideway in the second of said end members, whereby the second named side arm is extensible laterally with respect to the device.

3. A device of the class described comprising a pair of upright end members formed with their adjacent faces inclined oppositely from the base upward, a plurality 5 of horizontally aligned bottom slats arranged between the end members, alternate slats being rigidly secured to the same end member and arranged to enter recesses in the bottom wall of the opposite end member when the 10 device is in its retracted position, means for limiting the extensible movement of the end members, an extensible side arm having one end rigidly secured to a side edge of one of the end members and its opposite end secured to the corresponding side edge of the other end member, a second side arm having one end secured to a transversely extending 15 guide member slidable in a guideway in one of the end members and having its opposite end secured to a similar transversely extending guide member slidable in a guideway in the second of said end members, whereby the second named guide arm is extensible 20 laterally with respect to the device, means for limiting the extensible movement of said second named guide arm, an extensible tubular member having its ends secured to the adjacent faces of said end members intermediate the length thereof and in position to engage with cards placed between said end members, and a handle secured to each of the remote faces of said end members. 25
4. A device of the class described comprising a pair of upright end members arranged to face each other, a plurality of 30 bottom slats, certain of said slats being rigidly secured to one of the said end members, while the remaining slats are rigidly secured to the other end member, whereby the ends are movable longitudinally with respect to the device, means for limiting the longitudinal movement of said end members, and an extensible side arm connected with the side edges of said end members. 35 40

JOHN EMMONS BEMIS.
